UNITED STATES PATENT OFFICE.

ISAAC G. KELLEY, OF MINNEAPOLIS, MINNESOTA.

HOLDER FOR CLEANERS.

1,076,888.

Specification of Letters Patent.

Patented Oct. 28, 1913.

Application filed March 29, 1913. Serial No. 757,485.

To all whom it may concern:

Be it known that I, ISAAC G. KELLEY, a citizen of the United States, residing at Minneapolis, in the county of Hennepin and State of Minnesota, have invented a new and useful Improvement in Holders for Cleaners, of which the following is a specification.

An object of this invention is to provide a device for cleaning purposes which can be converted at will into a mop, a scraper, a scrubbing brush or a brush for sweeping purposes and the invention comprises the combination and arrangements of parts to be hereinafter fully set forth in the following description and particularly pointed out in the claims.

In the accompanying drawing forming part of this specification, Figure 1 is a perspective of my invention shown with a scrubbing brush attached, a portion of the handle of the head being broken away; Fig. 2 is another perspective view when the device is in inverted position showing a mop attached thereto, a portion of the handle in this construction also being broken away; Fig. 3 is a perspective of the form of back which carries a scraper; Fig. 4 is a plan of the head looking at the face which joins to the back, and Fig. 5 is a detail of one of the backs partly in section.

In the drawing A indicates a head which is in the form of an elongated block to the upper surface of which a handle B is suitably attached. On the lower surface of this block what I choose to term a back C is detachably mounted. A plurality of backs of similar construction are provided for use with my invention, one being constructed with a brush D on its lower surface for scrubbing or sweeping purposes, another as illustrated in Fig. 2 with a mop E and another with a scraper F. These backs are adapted to be secured in turn to the head by pairs of springs G and H, said pairs being disposed on the opposite sides and near the ends of the head. These springs are of similar construction and each consists of a strip of spring material secured to the side of the head such as by screws I and extending over the side of the back thus serving to engage and prevent lateral movement of the back on the head.

To the inner faces of each pair of springs G and H a longitudinal holding rod J is secured, the corresponding inner ends of

which are turned in to form stop shoulders K against one end of the back and the corresponding outer ends turned out to form guides L which serve to direct the back into engagement with the head. The opposite sides of the back are provided with longitudinal grooves M into which the holders J are received to engage and support the back. When the back is inserted between the holders and against the stops K the outer ends of the holders lock the back on the head, the inner surface of the grooves M being notched to form shoulders N with which the catch shoulders O on said holders engage to prevent the withdrawal of the back until the supports are spread at their outer ends. By the construction described the backs are interchangeable upon the head and are adapted to be easily fastened to or detached from the head.

The back may be constructed with various devices for cleaning and scrubbing purposes, for instance as illustrated in Fig. 1, it is shown with a brush for scrubbing. By constructing the back with longer bristles the brush is adapted for sweeping purposes. As illustrated in Fig. 2 the back is shown constructed with a mop which is detachably secured thereto by means of the hinged spring arm P, the free end of which is engaged below the spring fastener Q. As illustrated in Fig. 3 the back is provided with a scraper F in the form of a rubber or flexible strip R which is fastened thereto against a shoulder piece S by means of the clamp T.

In accordance with the patent statutes I have described the principles of operation of my invention together with the apparatus which I now consider to represent the best embodiment thereof but I desire to have it understood that the construction shown is only illustrative and that the invention can be carried out by other means and applied to uses other than those above set forth within the scope of the following claims.

Having described my invention, what I claim as new and desire to protect by Letters Patent is:—

1. A cleaner holder including a head, pairs of leaf springs on each side of the head and extending beyond the same, and a cleaner engaging strip connected to each pair of springs and having stop lugs at one end and catch shoulders at the other, said strips being extended beyond their catch shoulders into flaring guides.

2. A cleaner holder including a head, pairs of leaf springs on each side of the head and extending beyond the same, and a cleaner engaging strip connected to each pair of springs and having stops at one end and catch shoulders at the other.

3. A cleaner holder including a head, pairs of leaf springs on each side of the head and extending beyond the same and

a cleaner engaging strip connected to each 10 pair of springs.

In testimony whereof, I have signed my name to this specification in the presence of two subscribing witnesses.

ISAAC G. KELLEY.
